LIQUID SOAP DISPENSING DEVICE

Filed Feb. 8, 1929

FIG. 1.

INVENTOR
Louis Kooperstein
BY
A. Lee Helms
ATTORNEY

UNITED STATES PATENT OFFICE

LOUIS KOOPERSTEIN, OF ASTORIA, NEW YORK, ASSIGNOR TO WEST DISINFECTING COMPANY, OF LONG ISLAND CITY, NEW YORK, A CORPORATION OF NEW YORK

LIQUID-SOAP-DISPENSING DEVICE

Application filed February 8, 1929. Serial No. 338,480.

The object of the invention is to provide a dispensing apparatus applicable to a lavatory top plate. The primary soap receptacle is located below the lavatory plate, a discharge nozzle being disposed above the plate together with an operating plunger for a pump valve and conduit elements which operatively communicate with the interior of the soap receptacle. The invention will be described with reference to the accompanying drawings in which

Fig. 1 is a sectional elevation of an embodiment of the invention, and

Fig. 2 is an enlarged section on the line 15 2—2 Fig. 1.

In the drawings A indicates the main casing of the device, the casing being formed with a depending tubular member 1 at the top of which the casing is outwardly flared 20 providing an annular shoulder 2. The casing is also formed with a nozzle 3. The casing is applied by passing the tubular extension 1 through an opening in the lavatory top 4 after which nut 5 is turned upward on the 25 threaded tubular member to clamp the device in position. A washer 6 may be interposed between the lavatory plate and nut 5.

The bore of tubular member 1 is slightly reduced towards its lower end and into said 30 reduced section is fitted the upper end of a tube 7 the tube being held in place by a set screw 8. The end of tube 7 is threaded to receive a pump casing 9.

Extending centrally of tubular member 1 and tube 7 is an operating rod 10. The rod at its lower end enters pump casing 9. Within the casing the rod is flanged at 11 to serve as an abutment or stop for a washer 12, the latter being held in place by a shouldered 40 thumb nut 13 threaded on a reduced section of the rod below flange 11. Washer 12 engages the walls of the annular bore 9a of the valve casing, the base of the bore being narrowed and communicating with a ball-holding chamber 14, enclosing a ball valve 15, the ball normally shutting off an air inlet 16. Within bore 9a is a spring 16 which engages thumb nut 13 and serves to maintain rod 10 normally in an upper position.

50 The upper end of rod 10 is connected to or

engaged by a plunger comprising stem 17 and a button 19. Compression of the plunger will impart a downward movement to the rod 10 and will actuate the pump comprising the elements above described.

Communicating with bore 9a of the pump casing is a duct 20 having horizontal and vertical branches. The vertical branch at its top is somewhat enlarged to receive the lower end of a pipe 21. Pipe 21 extends upwardly through a suitable aperture formed in the casing A and depending member 1, and at its top the pipe communicates with a bore 3a formed in nozzle 3.

In the operation of the device, downward movement of plunger comprising elements 17 and 19, guided by bearing plug 18 threaded in casing A, will through rod 10 impart a downward and operative movement to the pump against the tension of spring 16. As explained above the pump casing and dependent tubular member 1 will be disposed within a liquid soap-containing receptacle. Soap which has entered bore 9a by a previous upward or suction movement of the pump will in said operative movement of the pump be forced through duct 20 and thence upwardly through tube 21 for discharge through nozzle 3.

One of the primary advantages of the device resides in the simplicity of construction and lightness of operation. The pump is formed quite independently of the nozzle, and the nozzle top forms the main casing of the device so that a very rigid connection to the lavatory top is provided. The integral depending tubular member of the casing A receives the nut 5 by means of which the device is clamped to the lavatory top. The tubular member 21, by means of which the soap passes from the pump to the nozzle, can be detached for cleaning, and all of the parts may very quickly be disassembled and reassembled for cleaning, repair or replacement.

Having described my invention what I claim and desire to secure by Letters Patent is as follows: it being understood that various modifications may be made in the form and arrangement of the embodiment shown. For example, the soap container 21a may be

supported in any suitable manner. In the present instance, however, the container 21 α is shown as having a cap 22 secured to a threaded neck member 23, the latter being threaded upon tubular extension 1 of the faucet casing.

I claim:

In liquid soap dispensing apparatus, a faucet casing formed as a cast member having a longitudinally extending bore, a laterally offset faucet neck and a depending externally threaded tubular extension, an operating rod extending through said bore and projecting below the extension, said rod 10 lying parallel with a second bore formed in the casing and extending longitudinally of the tubular extension and communicating with a discharge bore formed in the faucet neck portion of the casing, a valve casing, a 15 tubular member connecting the valve and the depending tubular section of the first mentioned casing, a pump mechanism adapted to be operated by said rod and in register therewith, a tube detachably connecting a 20 discharge passageway formed in the valve casing and said second longitudinal bore formed in the faucet casing extension, a plug threaded in the upper end of the first-named longitudinal bore and a plunger carried by 25 the plug and adapted to operatively engage the said rod.

In testimony whereof, I have signed my name to this specification.

LOUIS KOOPERSTEIN.
